UNITED STATES PATENT OFFICE.

CHARLES F. KARSTENS, OF FOND DU LAC, WISCONSIN.

FOLDING TABLE.

Application filed May 21, 1925. Serial No. 31,843.

My invention is a folding table, and it consists in the combinations, constructions and arrangements herein described and claimed.

5 An object of the invention is the provision of a table of simple construction which will be strong and rigid when set up and is adapted to be folded to take up but very little space and so that a plurality of the 10 folded tables can be stacked so as to require but relatively little space for storage or transportation.

A further object of the invention is the provision of a table having a top and legs 15 hinged to the top and foldable against the underside of the table top, together with novel and efficient means for holding the legs releasably either in folded position or in top supporting position, as desired.

20 Other objects and advantages of the invention will be apparent from the following description, considered in conjunction with the accompanying drawings, in which—

25 Figure 1 is a perspective view showing the table in set up position and looking at the table from a point below the level of the table top,

30 Figure 2 is a plan view of the table with the legs folded against the underside of the top, the folded table being shown upside down, and

Figure 3 is an edge view of a plurality of the folded tables stacked.

The improved table comprises a top 1 which may have any desirable configuration and may be made of any suitable material, preferably of wood. The top shown in the drawing is rectangular. This top is reinforced by a plurality of stiffening bars or 35 cleats 2 which extend transversely of the top in spaced relation and are secured to the underside of the table top by screws 3 or like fastening devices. These bars 2 may also serve as connecting members in the 40

45 event that the top 1 should be made of a plurality of longitudinally separable sections, as for example of a plurality of boards of equal length placed side by side in the same plane. The cross bars 2 also have another function which will be hereinafter pointed out.

Two cross attaching strips 4 of less thickness than the bars 2 are secured to the underside of the top 1 by screws 5 or like fastening devices. The respective attaching strips 4 are shown as being parallel to each other

and as being secured to the table top adjacent to although spaced from the opposite ends of the table top, being inwardly of the end cross bars 2.

60 Two supporting members for supporting the table top in spaced parallel relation to a floor or like supporting surface are comprised in the embodiment of the invention which is exhibited in the drawings. Each of 65 these supporting members comprises a pair of legs 6 having the upper end faces thereof, indicated at 7, formed to complement the under faces of the attaching strips 4 so that each pair of legs 6 will be disposed in 70 a plane perpendicular to the plane of the table top 1 when the upper faces 7 of such legs are in flatwise contact with the underside of one of the attaching strips 4. The legs 6 of each pair are connected by a cross 75 piece 8 which is rigidly secured at its opposite ends to the middle portions of the legs and holds the legs in spaced relation. The legs 6 of each pair are attached at their upper ends by hinges 9 to the inner side of 80 one of the attaching strips 4 so that the pair of legs can be swung from position close to the underside of the top 1 and inwardly of the attaching strip to position to abut the lower face of the attaching strip flatwise at 85 the upper end of the legs and to lie in a plane perpendicular to the plane of the table top, or vice versa.

85 Each pair of legs 6 of course is attached to a different attaching strip 4. When the pairs of legs are folded against the underside of the top 1 as shown in Fig. 2, these legs and the cross connecting strips 8 are entirely disposed between the planes of the outer faces of the cross bars 2 and the table top 1, and thus will be protected against injury 90 when the folding table is placed upon a flat supporting surface or a plurality of the folded tables are stacked one upon another as shown in Figure 3.

95 Each pair of legs is releasably and firmly retained in active top supporting position by means of a folding brace which comprises a pair of sections 11 and 12. The section 11 is attached by a hinge 13 at its outer end to the cross piece 8 of the associated pair of legs to swing about a horizontal axis. The section 12 is attached at its outer end by a hinge 14 to the underside of the top 1 to swing about a horizontal axis. The adjacent or inner ends of the sections 11 and 12 are connected by a hinge 100

15 and are cooperatively beveled so that the sections 11 and 12 will not extend in a straight line when the folding base is extended as shown in Figure 1 and the adjacent ends of the sections of the base abut each other flatwise but will diverge at their upper sides from their meeting ends at an angle slightly less than 180° . The engagement of the meeting ends of the sections 11
10 and 12 of each brace therefore tends to hold the brace extended. However, the invention provides other means for holding the brace extended more positively, although releasably. Such holding means comprises
15 a substantially U-shaped spring locking member 16 having the arms thereof pivotally attached to the section 11 of the associated holding brace adjacent to the inner end of the section so that the spring locking member 16 is swingable about an axis parallel to the axes of the hinges 13, 14 and 15 and is swingable to and from position to cause engagement of the web of the substantially U-shaped latching member with
20 a groove or notch 17 in a stop or keeper block 18 which is secured to the underside of the associated attaching strip 4. The arrangement is such that the spring locking member 16 is placed slightly under compression when the associated folding brace is extended and the web of the spring locking member is in engagement with the notch or groove 17 of the associated block 18.
25 The brace 11-12, the pivoted spring latch 16 and the associated top supporting member 6-8-6 may all be held releasably against movement from position close to the underside of the top 1, as shown in Figure 2, by a retaining button 19 which is supported on a vertical pivot element 20 at the underside of a carrying block 21 which is secured to the underside of the top 1, the button 19 being swingable about the axis of the pivot element 20 to and from position
30 to prevent downward swinging movement of the folded pivoted latch member 16, and brace 11-12. The associated top supporting member of course will be supported against swinging downward from folded position when the brace 11-12 that is associated with that top supporting member is held folded.

From the foregoing description of the various parts of the device, the operation thereof may be readily understood. The folding parts of the table will be protected from injury when in folded position by the cross bars 2 and the table top. These folding elements will be securely held against accidental displacement from folded position. When the table is in set up position, the top supporting member will be firmly braced and the set up table will have relatively great strength and rigidity.

Obviously, my invention is susceptible of embodiment in forms other than that illustrated in the accompanying drawings and I therefore consider as my own all such modifications and adaptations of the form of the device herein described as fairly fall within the scope of the appended claim.

I claim:—

A folding table comprising a top, a pair of top supporting members hingedly attached to the top and each being swingable from position substantially at right angles to the top to position close to the underside of the top and substantially parallel with the top, a folding brace adapted when extended to firmly retain the top supporting member with which it is associated in substantially right angular relation to the top, said brace comprising a pair of sections respectively hinged at their opposite ends to the top and to one of said top supporting members and hinged together at their adjacent ends, the meeting ends of said sections of the brace being cooperatively beveled so that the sections of the brace will diverge at an angle slightly less than 180° when said brace is extended, said angle of slightly less than 180° being subtended by the sides of the section of the brace which are proximate to said top when the brace is extended, a spring retaining member pivotally attached at one end to one of said sections of the brace, and a block fixed to the top and having a groove adapted to be engaged by the free end of said spring retaining member, whereby said spring retaining member will be releasably held under compression when in position to prevent folding of said brace.

CHARLES F. KARSTENS.
